UNITED STATES PATENT OFFICE

CHARLES R. MINTER, OF GORDON, GEORGIA

BEDSTEAD AND BED BOTTOM

Application filed October 20, 1927. Serial No. 227,523.

This invention relates to improvements in bedsteads and bed-bottoms, and has for one of its objects to provide novel and serviceable devices of this kind of which the latter shall be yielding and yieldingly supported to the end that the maximum of comfort may be attained and of which the former shall be adapted to conceal the bed-bottom support means to the end that it shall be neat and attractive in appearance.

With the foregoing and other objects in view, the nature of which will become apparent as the description proceeds, the invention consists of the construction, combination and arrangement of parts herein-after fully described and claimed, and illustrated in the accompanying drawings, wherein:

Figure 1 is a sectional view taken on a plane extending vertically and centrally through a bedstead and bed-bottom constructed in accordance with my invention.

Figure 2 is a sectional view taken on the horizontal planes indicated by the line 2—2 of Figure 1.

Figure 3 is a detail top plan view of a fragmentary portion of the bed-bottom, and

Figure 4 is a sectional view taken on the planes indicated by the line 4—4 of Figure 1. Corresponding and like parts are referred to in the following description, and designated in the several views of the accompanying drawings, by similar reference characters.

The bedstead comprises a head member 1, foot member 2 and side rails 3. The bedstead may be made of wood or metal, and the head and foot members 1 and 2 thereof are hollow. Top bars 4, bottom bars 5, and intermediate bars 6 are located within the head and foot members 1 and 2 and extend transversely of the bedstead. The bars 4 and 5 are fixed to the head and foot members 1 and 2 in any suitable manner, and the bars 6 are free to move vertically with respect to said members. The floating bars 6 are suspended from the bars 4 by coil springs 7. Coil springs 8 which are lighter than the coil springs 7, are secured to the bars 5 and 6 and serve to cushion the reaction of the

springs 7. The springs 7 and 8 are located within the head and foot members 1 and 2 which are provided at their inner sides with vertical slots 9. Head levers 10 and foot levers 10^a of angular formation, are pivotally secured through the medium of their horizontal arms to the bars 6. The horizontal arms of the levers 10 and 10^a pass through the slots 9. The vertical arms of the levers 10 and 10^a extend downwardly, and secured to the lower ends of these arms is a coil spring 11 which functions to normally maintain the horizontal arms of the levers in horizontal position.

The bed-bottom comprises flexible rods 12, head links 13 connected by cross bars 14, foot links 15 connected by cross bars 16, and spring rods 17 and 18. The rods 12 are connected to the links 13 and 15 adjacent the upper ends of the latter. The rods 17 are connected to the lower ends of the head links 13 as shown at 19, and are pivotally connected as shown at 20 to the foot levers 10^a. The rods 18 are connected as at 21 to the lower ends of the foot links 15, and are pivotally connected as at 22 to the head levers 10. The lower ends of the head links 13 are connected to the head floating bar 6 by stay rods 23, and the lower ends of the foot links 15 are connected to the floating foot bar 6 by stay rods 24. Stay springs 25 are secured at their upper ends to cross bars 26 which are located below the rods 12 and slidably connected thereto by sleeves 27. The lower ends of certain of the springs 25 are slidably connected to the rods 17, and the lower ends of the remainder of the these springs are slidably connected to the rods 18. The connection between the springs 25 and rods 17 and 18 is established through the medium of loops 28 formed on the lower ends of the springs and embracing the rods. The springs 25 may, since they are slidably connected to the rods 12, 17 and 18, be adjusted towards and from the transverse center of the bed-bottom as occasion may require.

The mattress 29 may be supported directly from the bed-bottom by being placed upon the flexible rods 12 or it may be supported from the bed-bottom through the

medium of springs 30, as shown in Figure 1. The springs 30 are secured at their lower ends to the rods 12 and at their upper ends to longitudinal tie bars 31.

5 As the rods 12 are flexible, and as they are held under tension by the spring 11, spring rods 17 and 18, and springs 25, the bed-bottom possesses the desired elasticity. In view thereof, and as the bed-bottom is 10 yieldingly suspended from the bedstead, it will afford the maximum comfort. The bed-bottom is yieldingly maintained in a horizontal position by coil springs 32 that are secured to the upper ends of the links 13 and 15 and to the floating bars 6. These springs and the springs 8, which latter cushion the reaction of the springs 7, assist in rendering the bed-bottom comfortable.

It should be understood that the drawings 20 are merely illustrative and do not pretend to give exact proportions. Furthermore, the said drawings are illustrative of a preferred construction, it being my expectation that various changes and modifications may be 25 made without departing from the spirit and scope of my invention.

What is claimed is:—

1. A bed-bottom comprising levers, pivot members therefor, spring means supporting 30 the levers, pivot members connecting the levers to the spring supporting means, inclined links, flexible rods secured to the upper ends of the links, spring rods secured to the lower ends of the links and to the levers, stay 35 springs secured to and between the flexible rods and spring rods, and stay rods secured to the lower ends of the links and to the pivot members of the levers.

2. In combination, a bedstead, head levers, 40 foot levers, spring means supported by the bedstead and connected to and supporting the levers, pivot members connecting the levers to the spring supporting means, inclined head and foot links, flexible rods connecting the upper ends of the head and foot links, spring rods secured to the lower ends of the head links and to the foot levers, and spring rods secured to the lower ends of the foot links and to the head levers.

50 3. In combination, a bedstead, head levers, foot levers spring means supported by the bedstead and connected to and supporting the levers, pivot members connecting the levers to the spring supporting means, inclined head and foot links, flexible rods connecting the upper ends of the head and foot links, spring rods secured to the lower ends of the head links and to the foot levers, spring rods secured to the lower ends of the foot links and to the head levers, and stay springs 55 slidably connected to the flexible rods and to the springs rods.

4. In combination, a bedstead; head levers, 60 foot levers, spring means supported by the bedstead and connected to and supporting

the levers, pivot members connecting the levers to the spring supporting means, inclined head and foot links, flexible rods connecting the upper ends of the head and foot links, spring rods secured to the lower ends of the head links and to the foot levers, spring rods secured to the lower ends of the foot links and to the head levers, and stay rods secured to the pivot members and to the lower ends of the links.

5. In combination, a bedstead, head levers, 70 foot levers, spring means supported by the bedstead and connected to and supporting the levers, pivot members connecting the levers to the spring supporting means, inclined head and foot links, flexible rods connecting the upper ends of the head and foot links, spring rods secured to the lower ends of the head links and to the foot levers, spring rods secured to the lower ends of the foot links and to the head levers, stay springs 80 slidably connected to the flexible rods and to the spring rods, and stay rods connected to the pivot members and to the lower ends of the links.

6. In combination, a bedstead, a head bar, means yieldingly supporting the head bar from the bedstead, head levers pivoted to the head bar, a foot bar, means yieldingly supporting the foot bar from the bedstead, foot 90 levers pivoted to the foot bar, springs connecting and opposing downward movement of the head and foot levers, and a bed-bottom connected to and supported from the levers.

7. In combination, a bedstead, a head bar, means yieldingly supporting the head bar from the bedstead, head levers pivoted to the head bar, a foot bar, means yieldingly supporting the foot bar from the bedstead, foot levers pivoted to the foot bar, springs 100 connecting and opposing downward movement of the head and foot levers, a bed-bottom connected to and supported from the levers, and means for cushioning the reaction of the suspending means.

In testimony whereof I affix my signature.
CHARLES R. MINTER.
